(74) Attorney, Agent, or Firm—Fleit Kein Gibbons Gutman Borgini & Bianco; Paul D. Bianco; Martin Fleit

(57) **CLAIM**

The ornamental design for a pedestal sink, as shown and described.

DESCRIPTION

FIG. 1 is a front view of the pedestal sink of the subject invention;

FIG. 2 is a top view thereof;

FIG. 3 is a side view thereof; and,

FIG. 4 is a perspective view thereof.

The broken line representations are for illustrative purposes only and form no part of the claimed design.
